ary 12, 1945, Serial No. 577,439

11 Claims. (Cl. 196—52)

1 The present invention in its specific aspects relates to the catalytic conversion of hydrocarbons into lighter hydrocarbons of lower-boiling point or hydrocarbons otherwise altered in structure. In certain of its aspects the invention is particularly concerned with hydrocarbon conversions such as the catalytic conversion or cracking of high-boiling petroleum oils to low-boiling products within the gasoline boiling range.

The invention is especially concerned with the catalytic conversions of hydrocarbons involving two stages, a conversion stage wherein the hydrocarbons undergoing treatment are contacted with the catalyst under conditions adapted to effect the desired conversion, and a regeneration stage wherein the carbonaceous deposit formed on the catalyst during the conversion stage is eliminated. In its preferred aspect, my invention contemplates particularly an improved process involving a conversion stage wherein vapors of the hydrocarbons undergoing treatment are contacted in a conversion zone with particles of a suitable catalyst; and a regeneration step wherein the used catalyst particles, after separation from the gaseous conversion products, are contacted with an oxygen-containing gas in a regeneration zone under suitable conditions to regenerate them by burning off deposited carbonaceous material.

This method of catalytically converting hydrocarbons has certain advantages arising particularly out of the relative intimacy of contact which it affords between the catalyst particles and the contacting gas both in the conversion and regeneration operations and the continuous character of the operation. It exhibits, however, various disadvantages, the elimination of which is one of the primary objects of my invention. One of these disadvantages is the problem of maintaining the temperature of the regeneration reaction within desired limits and in such manner as to eliminate the carbonaceous deposit on the catalyst to the desired extent without overheating of the catalyst.

The present application is a divisional application of my copending application Ser. No. 418,005, filed November 6, 1941, now U. S. Patent No. 2,369,523, issued February 13, 1945, and the latter application in turn being a continuation-in-part of my copending application Ser. No. 343,222 filed June 29, 1940. In the latter application, I have

2 disclosed several modifications of processes for controlling the temperature of the catalyst regeneration zone within desired limits by the charging of catalyst to the regeneration zone in a predetermined and controlled relationship with respect to certain of the variable operating conditions involved including the quantity of feed charged to the conversion zone. The present application is directed particularly to certain modifications disclosed in said copending application involving the feature of controlling the temperature of the regeneration zone by cooling a portion of the catalyst withdrawn from the regeneration zone in a zone distinct from the conversion zone and returning the cooled catalyst to the regeneration zone for the purpose of temperature control therein.

The foregoing and various other features and advantages of the invention will be apparent from the following detailed description thereof given with reference to the appended drawings which illustrate suitable process flow and arrangement of apparatus for its practice.

25 Figure 1 illustrates a suitable arrangement of apparatus and process flow involving the feature of introducing cooled regenerated catalyst to the regeneration zone for temperature control therein as applied to the catalytic conversion of high-boiling hydrocarbons to low-boiling hydrocarbons within the motor fuel boiling range.

30 Figure 2 is a modified embodiment generally similar to Figure 1 and involving the additional feature of recycling used catalyst to the conversion zone.

35 Fig. 3 is a modified form of process flow involving the feature of recycling cooled regenerated catalyst in a plurality of streams.

40 Fig. 4 is a modified embodiment generally similar to Fig. 1 and involving the feature of maintaining the velocity of vapor flow within certain preferred ranges.

Referring to Fig. 1, a suitable feed, for example a cracking stock such as a vaporized petroleum gas oil heated to a suitable temperature, is introduced through transfer line 12 leading from a conventional pipe still or other suitable source not illustrated. The feed vapors in transfer line 12 may be advantageously combined with a recycle oil fraction introduced through line 14, the

combined streams passing to the conversion stage through line 15. The oil passes through line 15 into pipe 16 constituting an extension of the conversion reactor 17. Hot preheated catalyst is supplied from collecting or surge drum 18 by helical feeder 19 and mixed with the oil in pipe 16. The upper surface of the body of catalyst in drum 18 is indicated by dotted line 60. Sufficient steam or other suitable gas to initially disperse the catalyst as discharged from feeder 19 is preferably introduced through line 20. Steam or other suitable gas may be supplied in greater quantities through line 20 when required. Operating conditions such as the ratio by weight of the catalyst to fresh feed stock may be maintained and regulated as set forth in detail hereinafter. The gaseous mixture of feed stock, catalyst and steam flows upwardly through reactor 17 during which flow conversion or cracking of the oil to the desired extent occurs.

Reaction products pass from the top of reactor 17 to a suitable separator system to separate the catalyst from the vaporous reaction products. That shown comprises a settling tank 21 in which the major proportion of the suspended catalyst is separated, the separated catalyst flowing by gravity from the bottom of tank 21 through conduit 22 to the top of a steam stripper tower 23 and the vapors containing a relatively small fraction of fine catalytic material are withdrawn at the top through line 24. These vapors pass through line 24 to a suitable separator such as a cyclone type of dust collector 25 wherein most of the remaining suspended catalyst is separated and then passed to tower 23 by gravity flow from the bottom of the separator through line 26.

Tower 23 serves to displace hydrocarbon vapors contained in the voids between the particles of catalyst and is suitably provided with baffles 27 to effectively expose the catalyst passing downwardly therethrough to the displacing action of a countercurrently flowing current of steam introduced at the base of the tower through line 28. Steam containing the oil vapors displaced from the catalyst is withdrawn from the top of the tower through line 29 and combined with the vapor stream from tank 21. Used catalyst falls from the bottom of tower 23 into a surge drum 30. The gaseous suspension withdrawn from separator 25 containing the gaseous conversion products, steam and a small residual amount of used catalyst is passed through line 31 to a suitable type of fractionator 32 wherein a low-boiling fraction such as gasoline and fixed gases may be separated from the high-boiling products such as light and heavy cycle gas oils. In the fractionator 32 the conversion products may, for example, be fractionated into a low-boiling fraction including gasoline and fixed gases withdrawn as overhead product from the fractionator through line 33, an intermediate product such as light gas oil withdrawn as a side cut through line 34, and a residual high-boiling fraction such as heavy recycle gas oil withdrawn through line 35, cooled in cooling coil 61, and pumped to storage through line 36.

In the bottom of fractionator 32 suitable means may be provided for separating residual catalyst present in the vapors introduced through line 31. As shown, these means comprise a line 37 through which a portion of the high-boiling fraction withdrawn through line 35 is returned to the fractionator over baffles 36 which deflect the vapors from line 31 into intimate contact with the returned fraction which consequently ad-

sorbs or scrubs out residual catalyst present in the vapor. After passing over baffles 36 the scrubbing liquid with the residual catalyst suspended therein collects in the bottom of fractionator 32 from which it is withdrawn through line 39 and pumped by pump 40 into line 14 for utilization as a recycle oil, as previously described.

Used catalyst is fed from drum 30, in which the upper surface of the catalyst mass is indicated by dotted line 62, by screw feeder 41 to pipe 42. A further stream of catalyst is introduced into line 42 from line 83, the latter stream consisting of cooled and previously regenerated catalyst, the quantity thus introduced being preferably regulated as hereinafter described. A suitable quantity of air is introduced to line 42 through line 43 supplemented if desired by steam introduced through line 45. The mixture of used and recycled catalyst is carried through line 42 by the current of oxygen-containing gas injected through line 43 to regeneration or combustion chamber 44 in which combustion of the carbonaceous deposit on the spent catalyst occurs during the passage of the catalyst therethrough.

Combustion gases bearing the regenerated catalyst pass from chamber 44 into a suitable recovery system for separating the catalyst. In accordance with the embodiment shown in Fig. 1, the stream of regeneration gas carrying the regenerated catalyst upon leaving the regeneration zone 44 is split into two streams, one portion being by-passed through valve 71 to line 70, and the other portion passing through valve 80 to separator 46. In separator or settling tank 46 most of the catalyst present in the stream introduced thereto is separated and flows downwardly therefrom through conduit 47 to surge drum 18. The separated gases containing a small residual amount of catalyst fines leave separator 46 at the top through line 48 and pass to a cyclone type of dust collector 49, wherein substantially complete separation of the catalyst is effected. The separated catalyst from collector 49 then flows downwardly through line 50 and is combined with the initially separated catalyst in drum 18 from which it is fed to the conversion stage by feeder 19. Drum 18 and feeder 19 may be suitably provided with heat insulation material to obviate loss of heat by the regenerated catalyst in its passage therethrough.

In the practice of my invention the quantity and temperature of regenerated catalyst recycled to the regeneration zone through line 70 may be suitably determined by the application of a generalized formula. In fixing the ratio (*r*), by weight, of the total catalyst charged to the regeneration zone relative to the fresh gas oil charged to the conversion zone for any particular oil and extent of conversion required, this ratio is determined under the other given or fixed operating conditions concerned in a manner adapted to assure the presence of the cool recycled catalyst in sufficient amount to absorb a definite minimum amount of the heat of regeneration by the application of the following formula:

$$r = \frac{CH}{S(T_1 - T_2)} \cdot K$$

In this formula *r* represents the catalyst-to-oil weight ratio as defined above; the symbol *C*, the fraction of the gas oil or other hydrocarbon charged, converted to coke or carbonaceous material and deposited on the catalyst during the conversion; *H*, the heat of combustion of the

coke or carbonaceous material expressed in B. t. u.'s per lb.; S, the specific heat of the catalyst; T₁, the maximum temperature in degrees Fahrenheit to which the catalyst is subjected during regeneration and the temperature of the catalyst upon withdrawal from this zone which is determinable by the "deactivation temperature" of the particular catalytic material involved, i. e. the temperature in excess of which the catalyst may not be heated without permanent and substantial injury to its catalytic activity; T₂, the temperature in degrees Fahrenheit of the total catalyst entering the regeneration zone represented by the weighted average temperature of used catalyst and cooled recycled catalyst entering the regeneration zone; and K, a coefficient having a lower limit determined by the extent to which expedients other than the heat absorption capacity of the catalyst may be employed to dissipate the heat of regeneration.

The quantity of catalyst recycled to the regeneration zone and the temperature thereof is preferably controlled in such manner that the value of K in the above equation is in excess of 0.2 and preferably in excess of 0.5, and may suitably be about 0.8 or even higher.

The preferred quantity and temperature of recycled catalyst may be expressed directly by a modification of the above basic equation as follows,

$$R_1 = \frac{CHK - RS(T_1 - T_3)}{S(T_1 - T_4)}$$

In the above equation the symbol R represents the ratio by weight of the regenerated catalyst charged to the conversion zone to the weight of oil charged to the same zone; T₃, the temperature of the used catalyst on entering the regeneration zone from drum 30; T₄, the temperature of the recycled catalyst on entering the regeneration zone from drum 16; and R₁, the ratio by weight between the quantity of catalyst recycled to the regeneration zone, and oil introduced into the conversion zone. The other symbols have the same meaning as in the basic formula or equation, and the coefficient K is subject to the same preferable values.

The fraction of regenerated catalyst for temperature control determined as given above, passes through an indirect heat exchanger 72 through which a cooling medium is circulated through lines 73 and 74. The cooled suspension of flue gas and catalyst then passes through line 75 into a separating zone 76 wherein flue gas is taken overhead through line 78 and separated catalyst is collected in the lower portion as indicated by line 77. Any catalyst remaining in the flue gas withdrawn overhead may be separated by a cyclone separator 79 or similar device and returned through line 81 to zone 76. Catalyst is fed from zone 76 by means of a screw conveyor 82 and suspended in air supplied through line 84 and carried through line 83 to transfer line 42 wherein it is mixed with used catalyst supplied by screw conveyor 41.

Any type of catalyst suitable for effecting the desired conversion may be employed in the practice of my invention. For the conversion or cracking of high-boiling fractions such as gas oil to low-boiling fractions such as gasoline, I regard cracking catalysts of the "alumina-silica" type as especially suitable, this term being inclusive of cracking catalysts such as certain types of activated clays or synthetically produced mix-

ture or compounds of alumina and silica. The circulated catalyst may be composed entirely of the active catalytic material and is preferably predominantly composed thereof. However, the active catalyst may be associated with supports, extenders or solid diluents which for the purpose of applying the formulae previously given are to be considered as part of the catalyst, since such solid diluents, etc., will function in a manner similar to the active part of the catalyst relative to the absorption of heat in the regeneration zone.

Referring to the modified form of flow illustrated in Fig. 2, this is similar to that of Fig. 1 in that it involves the recycling of cooled regenerated catalyst to the regeneration zone, but also involves additional novel features including the recycling of catalyst to the conversion zone without intervening regeneration thereof.

Regeneration gas containing regenerated catalyst suspended therein is withdrawn from regenerator 44' through line 86 and split into two streams, one stream passing through recycle line 70' controlled by valve 71' and the other stream 25 passing to the conversion side of the system by line 87 controlled by valve 80'. The recycled catalyst passing through line 70' as in the case of the embodiment shown in Fig. 1, is returned to the initial part of the regeneration zone after 30 cooling and separation from the flue gas carrier by means similar to those shown in Fig. 1 and designated by corresponding primed reference numerals.

The fluid suspension of regenerated catalyst 35 passing through line 87 may be passed directly to settling drum 88 through valve 89 and line 90, or all or a portion thereof may be bypassed through valve 91 and line 92 through a suitable cooler or heat exchanger 93 through 40 which a suitable cooling or heating fluid is circulated through lines 94 and 95. In passing through exchanger 93 the temperature of the catalyst is brought to that most suitable for the particular conversion reaction concerned. The fluid suspension passes from line 90 into settling drum 88 wherein most of the catalyst is separated from the flue gas and settles into the bottom of the drum. Flue gas bearing a residual amount of suspended catalyst 45 passes overhead from drum 88 through line 96 into a suitable separator such as cyclone separator 97 wherein substantially complete separation of the residual catalyst is effected and the separated catalyst returned from the bottom 50 of the cyclone through line 98 to drum 88.

From drum 88 the regenerated catalyst is fed into a stripping tower 99 by suitable feeding means 100. In tower 99, the catalyst flows downwardly over baffles 101 countercurrently to 60 a current of steam introduced through line 102. The stripping steam bearing with it any oxygen-containing gases previously entrained with the regenerated catalyst passes overhead through line 103 into cyclone 104 wherein any catalyst 65 particles entrained with the steam are separated and pass from the bottom of the cyclone to an accumulator drum 105 and are then returned to the bottom of tower 99 by suitable feeding means 106. The stripping operation serves to 70 remove any oxygen-containing gases present in the regenerated catalyst which might be detrimental in the subsequent conversion reaction. Stripped catalyst is fed from the bottom of tower 99 by suitable feeding means 107 into line 75 108 wherein it is suspended in the vapors of

the feed stock undergoing treatment and the suspension introduced into the conversion reactor 109. Additional catalyst may be added at this point by means of feeding means 110. Reaction products are withdrawn from the top of reactor 109 through line 111 and passed to a suitable settling drum 112 wherein most of the suspended catalyst drops out of suspension into the bottom of the drum. The conversion products pass overhead from drum 112 through line 113 and residual catalyst is separated therefrom in cyclone 114 from whence it is returned to drum 112 through line 115. The hydrocarbon conversion products are withdrawn overhead from cyclone 114 through line 150 and passed to a suitable fractionating system such as that indicated on Figure 1. From drum 112 a portion of the used catalyst may be recycled to the conversion zone by feeding means 110 without any intervening stripping operation, the proportions introduced into the reaction zone of regenerated catalyst from feeding means 107 and recycled catalyst from means 110 being adjusted to provide any desired activity of catalyst in the reactor.

Used catalyst is fed from the bottom of drum 112 into a suitable stripping system by feeding means 116 at the same rate that regenerated catalyst is fed to the reactor by feeding means 107. The stripping system is similar to that described in connection with the stripping tower 99 and includes a stripping tower 117 and a fines recovery system including cyclone 118, accumulator drum 119 and return feeding means 120. In passing through tower 117 the used catalyst is stripped of hydrocarbons entrained therewith which pass out from the system with the steam by line 121, and may be recovered therefrom by any suitable recovery means. Stripped used catalyst is fed from the bottom of tower 117 by suitable feeding means 122 and suspended in regeneration air introduced through line 123 and the suspension then passed through line 124 into the regenerator 44'. Recycled catalyst may be introduced into the regeneration zone by means 82', the regeneration steps thereafter being similar to those described in connection with Figure 1.

Referring to Figure 3, this illustrates a modification of the regeneration system shown in Figure 2, the distinctive feature being the recycling of cooled regenerated catalyst to the regeneration zone in a plurality of streams at spaced points in said zone. As in the case of Figure 1 the regeneration gas bearing the regenerated catalyst is split into two streams, one passing through line 131 to the conversion system and the other through a recycle line 132, the quantity of suspension in each stream being controlled by valves 133 and 134, respectively. The suspension of regenerated catalyst passes through recycle line 132 into settling drum 135 wherein most of the catalyst settles out into the bottom of the drum, and any residual catalyst carried out overhead from the drum by the flue gas is separated in a suitable cyclone separator 136 and returned to drum 135. Used catalyst from the conversion stage is supplied to the regeneration stage by suitable feeding means 138 and is suspended in part of the total air required for regeneration supplied through line 139, the quantity of air supplied at this point being controlled so that the combustion which occurs in zone A will bring the catalyst to a temperature approximating the maximum safe regeneration temperature when it reaches the point at which

cool recycled catalyst is first introduced. A plurality of streams of recycled regenerated catalyst is returned from drum 135 to the regenerator by means of pumps 140, 141 and 142 through lines 143, 144 and 145, respectively. Air is injected at the outlet of each of these pumps to convey the regenerated catalyst through coolers 146, 147 and 148, respectively. Using a plurality of streams as shown, the recycled catalyst is injected into the regenerator at a series of spaced points so that each injection of the cooled catalyst will drop the temperature in the regenerator by only a relatively small amount. Air is preferably introduced with each stream of recycled catalyst in amount such that the catalyst will be approximately at the maximum safe regeneration temperature when it reaches the next catalyst injection point. By this means the burning of the coke is accomplished at a high temperature level approaching the maximum safe regeneration temperature throughout the regenerator, and with the result that the time required for coke combustion is decreased. The diameter of the regenerator may be enlarged after any catalyst injection point as shown to increase its volume by an amount corresponding to air added at this point, thereby maintaining uniform velocity of flow. In addition to the flexibility of temperature control, this system has the added advantage that the injection of the cooled recycle catalyst will not drop the temperature in the regenerator to a point where combustion of coke on the partially regenerated catalyst may cease.

In the practice of my invention, the upward velocity of the regeneration gas through the regenerator may be varied over a wide range with attainment of reasonably satisfactory results. For a given quantity of gas introduced, this gas velocity will be dependent upon the cross-sectional area of the regenerator and varies inversely therewith. A range of gas velocity from about 1 to 25 feet per second is regarded as satisfactory in most instances. At the higher order of velocities the catalyst particles are carried along with the gas at a speed somewhat lower but approximating that of the gas, and accordingly the period during which the catalyst particles are in the regenerator is approximately the same but somewhat greater than the period of contact of the gas molecules with the catalyst. Also, under such condition the direction of movement of the catalyst particles upward through the regenerator is largely linear, as in the process flow of Figure 3. Certain distinctive advantages are obtained by the practice of my invention under conditions wherein a relatively low upward velocity of the regeneration gas through the regeneration zone is maintained, for example, a velocity of about 1 ft. per second, and generally velocities in the range of about 0.5 to 6 ft. per second and preferably within the range of 0.5 to 3 ft. per second. These velocity ranges are especially desirable with powdered catalyst consisting of small particles indiscriminately sized and smaller than about 100 microns. With widely different sized particles variation in these velocity ranges may be desirable. The conditions and advantages of the invention as thus practiced are illustrated by the process flow shown in Figure 4.

Referring to Figure 4, catalyst particles such as a powdered cracking catalyst are introduced through the valve 189 of a catalyst standpipe 181 into a stream of the feed vapors traveling at a relatively high velocity through the reactor inlet

line 152. Both the catalyst and vapors are heated prior to their mixture in line 152 to a temperature suitable for the subsequent conversion. Vaporized feed may be supplied to line 152 by a transfer line 153 leading from a pipe still heater or other suitable source of hot vaporized feed stock. In certain instances, the hydrocarbon feed may be introduced through line 153 entirely or partially in the liquid phase and the necessary vaporization produced upon the mixture of hot catalyst therewith. Catalyst thus introduced is picked up by the vapors and carried therewith through line 152 into a conical inlet 155 in the lower part of reactor 156. Reactor 156 is a vessel in the form of a cylinder or other suitable shape, having a relatively great cross-sectional area compared with the cross-sectional area of the vapor inlet line 152, and these relative proportions cause a corresponding reduction in the velocity of the vapors after their passage from inlet line 152 into the reactor 156. The velocity of the vapors in reactor 156 is preferably maintained relatively low and within such limits as previously given so as to produce a concentrated dense turbulent phase of the catalyst in this zone which state may conveniently be designated as "fluidized." This "fluidized" condition, in general, is characterized by the relatively high concentration of catalyst measured in terms of the quantity of catalyst per unit volume of reactor space, and by the low velocity of reactant vapors upwardly through the reactor. This condition is further characterized by the extensive turbulence or "internal recycling" of the catalyst particles throughout the reaction zone so that the temperature of the zone, regardless of whether the reaction involved is endothermic or exothermic tends towards uniformity throughout the zone and hence is characterized by the absence of a substantial temperature gradient. Also due to this extensive turbulence the particles tend to reach an average composition with respect to their carbon content throughout the zone regardless of whether the reaction concerned is one involving deposition of carbonaceous material or its removal. The level of the relatively dense fluidized phase is preferably maintained at the upper portion of the reaction zone as indicated by line 190.

The reactant vapors travel upwardly through the reactor in contact with the fluidized catalyst and during this period of contact undergo the desired conversion. Operating conditions in the reactor determined by variables such as the dimensions of the reactor, and the temperatures and rates at which reactant vapors and catalyst are supplied thereto, are maintained within such limits as to bring about the desired quality and extent of conversion.

The vaporous reaction products are withdrawn from the upper part of the reactor through a suitable outlet pipe or cone 157. The used or spent catalyst may be separated from the vaporous conversion products by any one of several suitable methods. According to that illustrated in Figure 4, the vapors pass from the upper portion of the reactor into the conical outlet 157 of decreasing cross-sectional area wherein their velocity is progressively increased and then into an outlet pipe 158 of relatively restricted cross-sectional area compared with that of the reactor. The vaporous conversion products mixed with spent catalyst pass through the outlet pipe 158 at a relatively high velocity into a settling chamber or collecting hopper 159 of such cross-sectional area that

the velocity of the vapors therein is preferably of about the same order of magnitude but may be more or less than the vapor velocity in reactor 156. A baffle 160 is preferably interposed directly in the path of the vapor mixture passing from pipe 158 whereby the mixture is directed laterally and downwardly thus functioning to propel catalyst particles present in the mixture out of the path of the vapor flow into a quiescent collecting zone defined by the outer walls of the outlet cone 157 and outlet pipe 158 and the lower inner walls of the settling or collecting hopper 159. Catalyst thus separated is withdrawn through suitable means such as catalyst standpipe 161 opening into the lower part of the collecting zone. A quantity of catalyst is preferably left at all times in said zone to maintain a level of catalyst therein at a substantial distance above the spent catalyst outlet opening as indicated by dotted line 162. Vaporous conversion products are withdrawn from the upper part of the collecting hopper through line 163 mixed with a relatively small portion of the catalyst originally present in the mixture passing through pipe 158.

Residual catalyst left in the vaporous conversion products leaving through line 163 is separated in a suitable recovery system such as cyclone separators or the like, and may be returned to the spent catalyst separated in chamber 159 through line 164.

A suitable stripping medium such as steam is introduced through a line 165 having suitable vapor distributing means 166, in the bottom of the mass of catalyst in the collecting zone to strip or displace hydrocarbon vapors absorbed thereon or entrained therewith and to maintain the mass in an aerated flowable condition. While only one such line 165 for introduction of the stripping medium is shown, it is to be understood that any suitable number may be employed and be so distributed throughout the collecting chamber as to assure the required stripping and aerating effects. The quantity of stripping steam is preferably such that its velocity in the collecting zone is low, that is, of the order of about 0.1 to 0.3 ft. per second. The stripping medium and stripped oil vapors pass out of chamber 159 overhead through line 163 together with the vaporous conversion products.

As illustrative of operating conditions suitably maintained in the conversion zone 156 in the cracking of high-boiling hydrocarbons to gasoline, reference is made to the data tabulated in the following Table 1 which sets forth conditions suitable for a large scale commercial unit for a given type of charging stock and capacity.

Table 1

Gas oil feed (31.1° API), bbl./day	10,000
Steam feed, lbs./hr	13,360
Reactor dimensions (a) ht., ft	28
Reactor dimensions (b) dia., ft	15
Feed weight ratio of regenerated catalyst-to-oil in line 152 (R)	5
Reactor temperature, inlet cone 155, °F	933
Reactor temperature (substantially throughout), °F	900
Reactor pressure, inlet cone 155, lbs./sq. in	13
Reactor pressure, outlet cone 157, lbs./sq. in	9.6
Vapor velocity, inlet, ft./sec	1.48
Vapor velocity, outlet, ft./sec	2.45
Ratio of weight of oil fed/hr. to weight of catalyst in reactor (w./hr./w.)	2.6

Catalyst time, seconds	290
Catalyst concentration, lbs./cu. ft.:	
(a) Inlet line 152	0.98
(b) Reactor	13
(c) Reactor outlet, line 158	0.6

In conveying the spent catalyst from the spent catalyst collecting zone to the regeneration zone suitable provision is made for any difference in pressure between these zones. A somewhat higher pressure is normally preferably maintained in the bottom or inlet portion of the regeneration zone than the pressure maintained in the collecting zone, and a head of suitably aerated or fluidized catalyst is preferably maintained in the outlet standpipe 161 of a sufficient magnitude to balance or exceed this differential pressure. For this purpose spent catalyst flowing through standpipe 161 is maintained in a condition in which it has the flow characteristics of a liquid by introducing in suitably regulated amounts an aerating medium such as steam through lines 167 at the bottom of and at other suitably spaced points along the length of pipe 161.

From the bottom of standpipe 161 spent catalyst is fed under the influence of the pressure head maintained therein and the pressure head provided by the mass of aerated catalyst in chamber 159 through a suitable feeding means such as a valve 168 into the regenerator inlet line 169.

Spent catalyst thus introduced is mixed with air or other suitable carrying medium such as steam introduced into pipe 169 by line 170'. In case air is employed, the quantity introduced is so controlled that the combustion of the spent catalyst in line 169 is not sufficient to raise the temperature of the catalyst beyond the maximum safe regeneration temperature.

The mixture of hot spent catalyst and carrying medium flows through line 169 into an inlet cone 170 at the bottom of the regenerator 171 where it meets and mixes with a stream of relatively cool recycled regenerated catalyst and air from cooler 172 and passes therewith upwardly through the regeneration chamber 171. Operating conditions in the regeneration chamber or zone 171 are suitably maintained to provide a condition similar to that maintained in the reaction zone with respect to a "fluidized" condition of the catalyst. This condition similar to that maintained in the reactor is characterized by the relatively large concentration of catalyst and low gas velocity maintained in the regeneration zone. Also, as in the case of the conversion zone, a high degree of turbulence and "internal recycling" may be maintained in the "fluidized mass" whereby its temperature and the average carbon content of the catalyst is substantially uniform throughout the reactor. The level of the relatively dense fluidized phase is preferably maintained at the upper portion of the reaction zone as indicated by line 191. During the course of the passage of the spent catalyst through regeneration chamber 171 combustion of the carbonaceous deposit thereon is effected to the required extent at an elevated temperature maintained below the safe maximum regeneration temperature by means of the cooled recycled catalyst.

Gaseous regeneration products (flue gas) and regenerated catalyst pass from the upper part

of the regenerator through an outlet 173 and into a separator 174 similar in design and mode of operation to separator 159, described in connection with the reactor. The major portion of the regenerated catalyst is separated and collected in a collecting zone at the bottom portion of the regenerated catalyst collecting hopper 174, and the gaseous combustion products together with a relatively small amount of regenerated catalyst pass out overhead from chamber 174 through line 175 to a suitable recovery system. Catalyst recovered from the flue gas leaving through line 175 may suitably be returned to hopper 174 through line 176.

Suitable means 177 and 178, similar to pipe 165 and distributor 166, are provided in the lower portion of hopper 174 to introduce a suitable medium such as steam to strip and displace flue gas absorbed or entrained with the regenerated catalyst and maintain the separated catalyst in an aerated flowable state. As in the case of the reactor a level of separated catalyst indicated by dotted line 179 is preferably maintained at a substantial distance above the catalyst outlet lines.

Regenerated catalyst is withdrawn from separator 174 in a split stream, a portion being sent through regenerated catalyst recycle line 180, and another portion through regenerated catalyst line 181 leading to the conversion or reaction system. Both catalyst outlet lines 180 and 181 are suitably pressure standpipes similar to standpipe 161 in that they are provided with means for introducing an aerating medium at suitable points along their length so as to maintain the catalyst flowing therethrough in a condition wherein it has the flow characteristics of a liquid, such means being lines 182 leading into recycle line 180 and lines 183 leading to catalyst outlet line 181. The quantity of catalyst withdrawn and recycled through line 180 and the cooling thereof is controlled so as to maintain the temperature in regeneration zone 171 within required limits as may be determined by the application of the mathematical formulae previously given.

Regenerated recycle catalyst is fed from the bottom of standpipe 180 through a suitable feeding means such as a slide valve 184 into an inlet line 185 leading to a heat exchanger or catalyst recycle cooler 172. Regenerated catalyst thus introduced is picked up by air introduced into line 185 through line 186, the quantity of air thus introduced being sufficient together with any air introduced through line 170' to effect combustion to the required extent in the regenerator 171. From line 185 the mixture of air and regenerated catalyst passes through exchanger or cooler 172 wherein the temperature of the recycled catalyst is lowered to the required degree by indirect heat exchange with a cooling medium circulated through the exchanger by lines 187 and 188.

Regenerated catalyst is fed to the conversion system from standpipe 181 through a suitable feeding means at the bottom thereof such as a slide valve 189 into the stream of vapors to be converted passing through line 152 as previously described.

To illustrate operating conditions suitably maintained in the regeneration zone in the practice of my invention, reference is made to the data tabulated in the following Table 2 wherein regeneration zone operating conditions are shown

corresponding to the conversion runs tabulated in Table 1.

Table 2

Spent catalyst, lbs./hr.	632,840	5
Cooled recycled catalyst, lbs./hr.	1,750,000	
Feed ratio by weight recycled/spent catalyst to the regeneration zone by lines 180 and 169	2.77	10
Feed weight ratio to the conversion zone 156 and to the regeneration zone 171 through lines 152 and 169 of spent catalyst-to-oil (R)		5
Feed weight ratio through line 180 to regeneration zone 171 of recycled cooled regeneration catalyst-to-oil (R ₁)		15
Feed weight ratio (R+R ₁) of total fed to regeneration zone-to-oil (r)		13.82
H, the heat of combustion of the carbonaceous deposit in B. t. u's.		18.08
S, the specific heat of powdered alumina-silica cracking catalyst		16,400
Inlet temperature to regenerator 171 by line 169, spent catalyst, °F. (T ₃)		900
Inlet temperature, recycled catalyst, °F., by line 180 (T ₄)		840
Temperature, weighted average of mixture recycled and spent catalyst, °F., through lines 180 and 169 (T ₂)		850
Temperature, regeneration chamber (substantially throughout), °F., and catalyst withdrawn through lines 181 and 180 (T ₁)		30
Regeneration dimensions:		
(a) Height, ft.		1,000
(b) Dia., ft.		35
Regeneration velocity:		
(a) Base		50
(b) Top		18
Air feed, lbs./hr.		1.62
Catalyst concentration regenerator, lbs./cu. ft.		2.59
Weight per cent of coke based on oil feed (100C)		88,350
Coke per cent by weight on spent catalyst		20
Carbon per cent by weight on regenerated catalyst (lines 180 and 181)		4.85
Catalyst contact time, seconds		1.3
Pressure in regenerator, lbs./sq. in.:		0.7
(a) Inlet cone		352
(b) Outlet cone		16
Value of symbol "K"		9

In the above example, combustion in the regeneration zone was effected in such manner that the carbonaceous deposit on the spent catalyst was only partially removed, that is, reduced from about 1.3% to about 0.7% by weight of the catalyst.

In the above example it is to be noted that the value of K is maintained in excess of 0.5 and consequently exemplifies the practice of the invention in accordance with the preferred range for this value. It will be further apparent that the quantity and temperature of regenerated catalyst recycled to the regeneration zone through line 180 pursuant to the above example conforms to the application of either of the two generalized equations given in the foregoing.

In accordance with the first generalized equation the feed weight ratio (r) of the total catalyst charged to the regeneration zone relative to the

oil charged to the conversion zone is determined by the following equation

$$r = \frac{CH}{S(T_1 - T_2)} \cdot K$$

Substituting in the above equation for the symbols the numerical values utilized in the above example (the value given for T₂ being approximated) gives the following

$$18.08 = \frac{.0485 \times 16,400 \times 0.75}{0.22(1000 - 850)}$$

Pursuant to the second generalized equation which is a modification of the first the preferred quantity and temperature of recycled catalyst is given by applying the following

$$R_1 = \frac{CHK - RS(T_1 - T_3)}{S(T_1 - T_4)}$$

Substituting in the above equation the numerical values for the symbols utilized in the above example gives the following

$$0.22 = \frac{.0485 \times 16,400 \times .75 - 5 \times .22(1000 - 900)}{.22(1000 - 840)}$$

It is to be noted that regeneration is effected pursuant to the above example without employing the conventional expedients for controlling the temperature of the catalyst during regeneration such as the provision of cooling surfaces within the regeneration zone or dilution of the regeneration air with large quantities of an inert gas.

The maintenance of a definite minimum concentration of carbonaceous material on the catalyst as exemplified by the above example, has important distinctive advantages. It assists in the regeneration reaction since the rate of combustion is accelerated and more readily controlled by the presence of an amount of carbonaceous material in excess of that which is to be removed by combustion. The retention of residual carbonaceous material also makes it possible to discharge the regeneration combustion gas with a relatively low percentage or in some cases, entirely free of oxygen, and the gas is thus better adapted for use for various purposes. Also, in certain instances, particularly in catalytic cracking in the presence of alumina-silica type of cracking catalyst such as "Super-Filtrol," the conversion reaction is facilitated by the presence of a small amount of residual carbon and in most instances the advantages obtained in regeneration by the maintenance of a residual carbon concentration will outweigh the disadvantages if any, resulting in the conversion stage. The residual carbon concentration maintained may depart somewhat from that given in the foregoing example wherein a "Super-Filtrol" type of alumina-silica cracking catalyst was employed. Preferably, this permissible range is confined to about 0.5% to 2.0%, by weight of the catalyst.

As an alternative, the process flow shown in Figure 4 may be modified to the extent of having line 180 and/or line 181 connect directly with the regeneration zone at a point below the level 191 of the dense catalyst phase. By this arrangement all but a small portion of the regenerated catalyst is withdrawn directly from the regeneration zone and only a relatively small quantity withdrawn overhead with the flue gas passing through line 175. In this alternative arrangement the high velocity outlet cone 173 may be omitted.

Although my invention is especially well ex-

emplified and advantageous as applied to the catalytic cracking of high-boiling hydrocarbons to lower boiling hydrocarbons within the gasoline boiling range, it may be applied with advantage to gas-solid contact processes generally and to other hydrocarbon conversions such as the catalytic reforming of naphtha fractions and to catalytic hydrocarbon conversion reactions generally, as will be apparent to those skilled in the art.

From the foregoing it will be apparent that the process therein described accomplishes the objects of my invention, and that various features thereof may be utilized to advantage either conjointly or separately. It will further be readily apparent to those skilled in the art that while the invention has been illustrated and described with respect to a preferred operation and examples, and with reference to suitable apparatus for its practice, the invention is not limited to such exemplifications but may variously be practiced and embodied within the scope of the claims hereafter made.

I claim:

1. The method of regenerating spent catalyst fouled with carbonaceous contaminants in a system wherein the finely divided spent catalyst suspended in a gas moves continuously through a plurality of regeneration zones which comprises, partially regenerating the moving catalyst in one zone, thereafter admixing cool regenerated catalyst with the partially regenerated catalyst, treating said mixture in another zone with a gas containing free oxygen under conditions such as to cause further substantial combustion of the carbonaceous contaminants and further regeneration of the partially regenerated catalyst.

2. The method of regenerating finely divided spent catalyst fouled with carbonaceous contaminants in a system wherein the spent catalyst moves continuously while suspended in air serially through a plurality of regeneration zones and is partially regenerated by the removal of a fraction only of the total carbonaceous contaminants in each of said zones which comprises limiting the fraction of contaminants removed in one of said zones to an amount removable by combustion with the oxygen of the suspending air without exceeding the maximum safe catalyst regeneration temperature and without substantial removal of heat from said zone by extraneous cooling means, removing another fraction of said carbonaceous contaminants by combustion with the oxygen of the suspending air in another of said zones under conditions wherein removal of heat by extraneous cooling means is necessary to prevent a temperature rise in the catalyst in excess of the maximum safe regeneration temperature, and recycling previously regenerated and cooled finely divided catalyst to the latter zone to maintain the temperature thereof within required limits.

3. In a catalytic process of cracking hydrocarbon oils wherein a powdered cracking catalyst is alternately suspended in and contacted with vapors of the oil thereby becoming contaminated with carbonaceous deposits and thereafter the contaminated catalyst particles are suspended in and contacted with an oxygen-containing gas to remove the carbonaceous deposit by combustion, the improved method of removing the carbonaceous deposits comprising withdrawing hot contaminated powdered catalyst directly from the cracking zone and commingling air therewith, passing the resultant

combustion-supporting suspension upwardly through an initial regeneration zone in which the temperature of the catalyst is permitted to rise to a level approximating but below the maximum safe regeneration temperature and partially removing the carbonaceous contaminants by combustion without removing heat by extraneous cooling means from the catalyst during its travel through said initial combustion zone, admixing the partially regenerated catalyst with an additional quantity of an oxygen-containing gas and cooled recycled regenerated catalyst and passing the resulting suspension through a subsequent regeneration zone to burn off an additional amount of said contaminants.

4. The method of regenerating spent catalyst fouled with carbonaceous contaminants which comprises moving the spent catalyst continuously and serially through a plurality of regeneration zones in contact with oxygen to effect combustion of carbonaceous contaminants, limiting the fraction of contaminants removed in one of said zones to an amount removable by combustion without exceeding the maximum safe catalyst regeneration temperature and without substantial removal of heat from said zone by extraneous cooling means, removing another fraction of said carbonaceous contaminants by combustion in another of said zones under conditions wherein removal of heat by extraneous cooling means is necessary to prevent an excessive temperature rise in the catalyst, and cooling the catalyst undergoing regeneration in said latter zone while in said zone by contact with previously regenerated and cooled catalyst to maintain the temperature thereof within required limits.

5. The method of regenerating spent catalyst fouled with carbonaceous contaminants which comprises moving the spent catalyst continuously and serially through a plurality of regeneration zones in contact with oxygen to effect combustion of carbonaceous contaminants, limiting the fraction of contaminants removed in one of said zones to an amount removable by combustion without exceeding the maximum safe catalyst regeneration temperature and without substantial removal of heat from said zone by extraneous cooling means, admixing cool regenerated catalyst with the catalyst partially regenerated in said first-mentioned zone, and treating the resulting catalyst mixture in another of said zones under conditions such as to cause further substantial combustion of the carbonaceous contaminants and further regeneration of the partially regenerated catalyst.

6. The method of regenerating spent catalyst fouled with carbonaceous contaminants which comprises moving the spent catalyst continuously and serially through a plurality of regeneration zones, treating the catalyst in one of said zones with oxygen to effect combustion of carbonaceous contaminants to an amount removable by combustion without exceeding the maximum safe catalyst regeneration temperature and without substantial removal of heat from said zone by extraneous cooling means, further treating said catalyst in another of said zones with additional oxygen under conditions wherein removal of heat by extraneous cooling means is necessary to prevent an excessive temperature rise in the catalyst, and cooling the catalyst undergoing regeneration in said latter zone while in said zone by contact with previously regenerated and cooled catalyst to maintain the temperature thereof within required limits.

7. The method of regenerating finely divided spent catalyst fouled with carbonaceous contaminants which comprises moving the catalyst while suspended in an oxygen-containing gas continuously and serially through a plurality of regeneration zones to effect combustion of carbonaceous contaminants, limiting the fraction of contaminants removed in one of said zones to an amount removable by combustion without exceeding the maximum safe catalyst regeneration temperature and without substantial removal of heat from said zone by extraneous cooling means, removing another fraction of said carbonaceous contaminants by combustion in another of said zones under conditions wherein removal of heat by extraneous cooling means is necessary to prevent an excessive temperature rise in the catalyst, and cooling the catalyst undergoing regeneration in said latter zone while in said zone by contact with previously regenerated and cooled catalyst to maintain the temperature thereof within required limits.

8. The method of regenerating finely divided spent catalyst fouled with carbonaceous contaminants which comprises moving the catalyst while suspended in an oxygen-containing gas continuously and serially through a plurality of regeneration zones to effect combustion of carbonaceous contaminants, limiting the fraction of contaminants removed in one of said zones to an amount removable by combustion without exceeding the maximum safe catalyst regeneration temperature and without substantial removal of heat from said zone by extraneous cooling means, removing another fraction of said carbonaceous contaminants by combustion in another of said zones under conditions wherein removal of heat by extraneous cooling means is necessary to prevent an excessive temperature rise in the catalyst, withdrawing catalyst from said last-mentioned zone, thereafter cooling said withdrawn catalyst, and recycling said cooled finely divided catalyst in suspension in an oxygen-containing gas to said last-mentioned zone to maintain the temperature thereof at the desired level.

9. The method of regenerating finely divided spent catalyst fouled with carbonaceous contaminants which comprises moving the catalyst while suspended in an oxygen-containing gas continuously and serially through a plurality of regeneration zones to effect combustion of carbonaceous contaminants, limiting the fraction of contaminants removed in one of said zones to an amount removable by combustion without exceeding the maximum safe catalyst regeneration temperature and without substantial removal of heat from said zone by extraneous cooling means, removing another fraction of said carbonaceous contaminants by combustion in another of said zones under conditions wherein removal of heat by extraneous cooling means is necessary to prevent an excessive temperature rise in the catalyst, cooling catalyst regenerated in said latter zone, and mixing said cooled regenerated catalyst with partially regenerated catalyst being intro-

duced into said latter zone to maintain the temperature therein within required limits.

10. The method of regenerating finely divided spent catalyst fouled with carbonaceous contaminants which comprises moving the catalyst while suspended in an oxygen-containing gas continuously and serially through a plurality of regeneration zones to effect combustion of carbonaceous contaminants, limiting the fraction of contaminants removed in one of said zones to an amount removable by combustion without exceeding the maximum safe catalyst regeneration temperature and without substantial removal of heat from said zone by extraneous cooling means, removing another fraction of said carbonaceous contaminants by combustion in another of said zones under conditions wherein removal of heat by extraneous cooling means is necessary to prevent an excessive temperature rise in the catalyst, withdrawing regenerated catalyst from said latter zone, cooling said withdrawn catalyst, and returning said cooled catalyst to said latter zone to maintain the temperature thereof within required limits.

11. The method of regenerating finely divided spent catalyst fouled with carbonaceous contaminants which comprises moving the catalyst while suspended in an oxygen-containing gas continuously and serially through a plurality of regeneration zones to effect combustion of carbonaceous contaminants, limiting the fraction of contaminants removed in one of said zones to an amount removable by combustion without exceeding the maximum safe catalyst regeneration temperature and without substantial removal of heat from said zone by extraneous cooling means, removing another fraction of said carbonaceous contaminants by combustion in another of said zones under conditions wherein removal of heat by extraneous cooling means is necessary to prevent an excessive temperature rise in the catalyst, withdrawing catalyst from said last-mentioned zone, cooling said withdrawn catalyst, and recycling said cooled finely divided catalyst in suspension in a gas to said last-mentioned zone to maintain the temperature thereof at the desired level.
